COVER FOR ELECTRIC KITCHEN UTENSILS

Bess Kaye, New York, N. Y.

Application January 31, 1958, Serial No. 49,461

Term of patent 7 years

(Cl. D81—10)

Fig. 1 is a front perspective view of a cover for electric kitchen utensils, showing my new design; and

Fig. 2 is a rear perspective view thereof, upside down.

The characteristic feature of my design for the cover disclosed resides in the pattern represented in full lines on the side thereof as shown.

I claim:

The ornamental design for a cover for electric kitchen utensils, as shown and described.
